(57) **CLAIM**

The ornamental design for a bag-in-box corrugated box, as shown and described.

DESCRIPTION

FIG. 1 is an upper view of a bag-in-box corrugated box, showing my new design;

FIG. 2 is a lower view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof.

FIG. 9 is an upper view of the bag-in-box corrugated box of FIGS. 1-8 in a partially-assembled state, prior to assembly into a fully-assembled state;

FIG. 10 is a lower view thereof;

FIG. 11 is a front view thereof;

FIG. 12 is a rear view thereof;

FIG. 13 is a first side view thereof;

FIG. 14 is a second side view thereof;

FIG. 15 is a top view thereof;

FIG. 16 is a bottom view thereof.

FIG. 17 is a lower view of the bag-in-box corrugated box of FIGS. 1-16 in a flattened, unassembled state, prior to assembly into a partially-assembled state;

FIG. 18 is an upper view thereof;

FIG. 19 is a front view thereof;

FIG. 20 is a rear view thereof;

FIG. 21 is a first side view thereof;

FIG. 22 is a second side view thereof;

FIG. 23 is a bottom view thereof; and,

FIG. 24 is a top view thereof.

The broken lines on edges in the drawings illustrate environmental structures of the bag-in-box corrugated box that form no part of the claimed design.

(Continued)

The dash-dot-dot-dash broken lines in the drawings illustrate portions of the bag-in-box corrugated box that form no part of the claimed design.
